SNUFFER FOR OIL LAMPS AND LANTERNS

Charles Irvine, Toronto, Ontario, Canada

Application March 21, 1935, Serial No. 12,147

1 Claim. (Cl. 67—77)

The invention relates to oil burning lamps and lanterns, and provides a simple and efficient device for automatically extinguishing the flame in the event of the lamp or lantern being overturned so that the attendant fire hazard will be eliminated.

The device is composed of a pair of arcuate plates having arms pivoted to suitable attaching means on the wick tube of the burner. The plates are furnished with fingers that normally retain them at each side of the wick in order that one or the other will swing over it should the lamp or lantern be upset.

A distinctive feature of the invention resides in the attaching means, which comprises a detachable member constructed to clip onto the wick tube and equipped with integral pintles on which the arms of the plates are swingably mounted.

20 The device is inexpensive to manufacture, efficient in operation, and can be attached to conventional lamps and lanterns.

Referring to the accompanying drawing:

25 Figure 1 is a side elevation of a lamp burner to which the present invention is shown applied.

Figure 2 is a top plan view thereof.

Figure 3 is a view at right angles to Figure 1, but showing the burner on its side with one of the snuffer plates thrown over the wick.

30 Figure 4 is a side elevation of the attaching clip.

Figure 5 is a plan view thereof.

Figure 6 is a side view of one of the snuffer plates, and Figure 7 an end view thereof.

35 Like numerals of reference indicate corresponding parts in each of the figures throughout the drawing of the invention.

In the drawing, the reference numeral 10 denotes the conventional burner of an oil lamp or lantern. This has the usual wick 11 fed through the burner by a wheel 12 to the tube 13 projecting from the top of the burner. The tube is flat sided and has rounded edges as customary. The orifice is flared slightly as denoted at 15.

40 The snuffer plates 16 are of identical construction and each is of an arcuate cross section taken on an arc of a circle the centre of which is the

pivotal axis of the arms 17. The plates are fashioned from sheet metal and the arms are integrally formed at right angles to the length of the plates. The plates are of a length slightly greater than the distance between the rounded edges of the wick tube and are each sustained by a finger as at 18 that abuts the respective side of the tube.

45 The arms are loosely pivoted on the aligned pintles 19 extending outwardly from the edges of the tube and borne by the attaching means.

10 The clip, constituting the attaching means, consists of a sheet metal member 20 extending across one side of the wick tube with the end 21 incurvate to fit about one of the rounded off edges of said tube. The other end 22 of the member 20 is also incurvate but is continued and out-turned as at 23 to form a latch. A strip of metal is cut and bent outwardly from each end of the clip to form the pintles on which the arms are pivoted.

15 The snuffer is attached as a unit to the burner 20 by placing the clip against a side of the wick tube with the end 21 hooked onto an edge thereof. The latch end 22 is then pressed so that it will click onto the other edge face of the wick tube. This securely holds it in place below the flared 25 orifice of the tube. It will be readily understood that in the event of the lamp or lantern being overturned, the snuffer plate that happens to be uppermost will be thrown over the wick to extinguish it.

30 What I claim is:—

In a snuffing device in which snuffing members are swingably arranged about a flat-sided wick tube, a detachable clip providing a support for said snuffing members adapted to be applied side- 35 wise of the wick tube, said clip consisting of a metal plate disposed across one side of the wick tube with an incurvate hook end engaged with an edge of the wick tube, the other end of said plate being bent incurvate to engage the other edge of 40 the wick tube and continued into an out-turned portion to form a latch that will snap sidewise on the wick tube, and a pair of aligned pintles struck out of the clip ends to swingably support the snuffing members. 45

CHARLES IRVINE.
